(No Model.)

W. J. NELSON.
PRUNING IMPLEMENT.

No. 425,820.

Patented Apr. 15, 1890.

INVENTOR,
W. J. Nelson
BY
C. D. Kneebaker
ATTORNEY.

UNITED STATES PATENT OFFICE.

WILLIAM J. NELSON, OF BLOOMFIELD, KENTUCKY.

PRUNING IMPLEMENT.

SPECIFICATION forming part of Letters Patent No. 425,820, dated April 15, 1890.

Application filed February 17, 1890. Serial No. 340,729. (No model.)

To all whom it may concern:

Be it known that I, WILLIAM J. NELSON, a citizen of the United States, residing at Bloomfield, in the county of Nelson and State of Kentucky, have invented certain new and useful Improvements in Pruning Implements; and I do hereby declare the following to be a full, clear, and exact description of the invention, such as will enable others skilled in the art to 10 which it appertains to make and use the same.

My invention relates to certain new and useful improvements in pruning implements, and has for its object to provide a pruning-cutter cheap, simple in construction, and efficient in 15 operation, and wherein a drawing shearing cut is given to the knife by the expenditure of a minimum amount of power, the force being directly applied to the knife, dispensing with the use of springs; and to this end my invention 20 consists in novel construction and arrangement of parts hereinafter fully described, and afterward definitely pointed out in the claims, due reference being had to the accompanying drawings, forming a part of this specification, wherein—

Figure 1 is a side elevation of my improved implement, showing in full lines the knife opened and in a position ready to make a cut, and in dotted lines the knife closed after the 30 cut has been made; Fig. 2, a rear elevation of a portion of the implement, showing the mechanism for operating the cutter-bar carrying the knife; and Fig. 3, a section taken through the line $\alpha\alpha$, Fig. 1.

Referring to the drawings, the letter A indicates the staff of my improved implement, having rigidly affixed to its upper end by bolts or otherwise a stationary knife *a*, whose cutting-edge *a'* is substantially straight and at 40 right angles to the staff A. The staff A is secured by means of bolts or rivets at its lower end to a wooden bar or pole B, which may be of any suitable or preferred length, and at a point about midway between its lower end and 45 the knife *a* said staff is deflected at an angle of about forty-five degrees, for the purpose hereinafter described.

C indicates a cutter-bar having secured to its upper end by means of bolts or rivets a 50 sickle-shaped knife *c*. The upper half of said cutter-bar C is slotted for a suitable distance, as at D, and is pivotally connected to the staff

A by means of a screw bolt or stud *d*, which passes loosely through the slot D and engages a screw-threaded opening in the staff A. The 55 lower end of the cutter-bar C terminates in an annular enlargement E, the central opening forming a true circle.

F indicates an annulus fitting snugly within the annular enlargement E, and is eccentrically pivoted to the staff A by means of a pivot screw or bolt *f*, passing through the periphery of the annulus and engaging the staff A. The 60 side of the annulus F next to the staff A is provided with a lug or overhanging lip *f'*, 65 which projects over the side of the annular enlargement E and serves to hold the parts in their operative position.

G indicates a lever formed integral with the annulus E and extending at a tangent therefrom, which is pivotally connected at its outer extremity with a rod H, which rod in turn is pivotally connected with a hand-lever I, the inner end of said hand-lever being pivoted to a bolt or eye secured to the bar B. In practice 70 I prefer to construct the bar B of wood, the knives *a* and *c* of the best knife-steel, and the remaining parts of wrought-iron.

The implement is designed to be held in the hands; but in pruning tall fruit-trees the bar 80 B may be joined to a second bar, which may rest upon the ground, and the end of the hand-lever D may be connected with a wire carrying at its lower end a stirrup adapted to be engaged by the foot for operating the device. 85

The operation of my device is as follows: The parts being in the position shown in Fig. 1, the twig or branch to be cut is grasped between the fixed knife *a* and the movable knife *c* and a downward pull given to the end of the 90 hand-lever I. By this means, through the medium of the rod H and lever G, the annulus F is rotated around the pivot *f* in the direction of the arrow, Fig. 1, causing it and the annular enlargement E, within which it rotates, to move outward and downward, thus drawing the cutter-bar C downward, and at the same time causing it to oscillate about the stud *d*, the sickle-shaped knife *c* being thus caused to approach the fixed knife *a* with a drawing 95 shearing cut, severing the twig or branch with little expenditure of power, and consequently with the minimum amount of strain and wear upon the knives and operative parts. 100

The action of the eccentrically-pivoted annulus F and its encircling annulus E is similar to that of the well-known valve or pitman eccentric; but by stalling and pivoting the cutter-bar, as shown, an oscillating and reciprocating motion is simultaneously given to said cutter-bar.

By deflecting the staff A from a straight line, as shown, the knife a, the movable knife c, and its operating mechanism are brought into the proper relative positions to give to said knife c the greatest cutting movement with the smallest amount of movement of the operative parts.

15 What I claim is—

1. In combination with the staff carrying at its upper end a fixed knife, a slotted cutter-bar secured to said staff by means of a stud passing through said slot and carrying at its 20 upper end a curved knife and provided at its lower end with an annular opening, and an eccentric fitted within said annular opening and pivoted to the staff, and means for rotating said eccentric, substantially as described.

25 2. In combination with the staff carrying a fixed knife, the slotted cutter-bar secured to the staff by a stud passing through said slot and carrying at its upper end a curved knife and provided at its lower end with an annular 30 opening, an eccentric fitted within said opening and pivoted to said staff and provided with a lever connected to a rod, and hand-lever for rotating said eccentric about its pivot, substantially as and for the purpose specified.

3. In combination with the staff carrying at 35 its upper end a fixed knife and at its lower end secured to a bar, a slotted cutter-bar secured to the staff by a stud passing through said slot and carrying at its upper end a curved knife and provided at its lower end with an 40 annular opening, an eccentric fitted within said opening and provided upon its under side with an overhanging lip and pivoted to said staff, a lever projected from the periphery of said eccentric, and a rod engaging said lever 45 and pivoted to a hand-lever secured to the bar carrying the staff, substantially as shown and described.

4. In combination with the staff A, bent as shown, and secured to the bar B and carrying a fixed knife a, the slotted cutter-bar D, secured to the staff by a stud d, passing through said slot and carrying a curved knife c at its upper end and provided with an annular opening E at its lower end, an annulus F, fitting 55 within the annular opening and provided with an overhanging lip f, and pivoted near its periphery to the staff and provided with a lever G, extending therefrom at a tangent, the rod H, and the hand-lever I, all arranged and operating substantially in the manner shown and described, and for the purpose specified.

In testimony whereof I affix my signature in presence of two witnesses.

WILLIAM J. NELSON.

Witnesses:

JOHN A. TERRELL,
N. W. MUIR.
